HAIR CURLER

Joseph Jacobs, Bridgeport, Conn.

Application March 23, 1940, Serial No. 325,494

3 Claims. (Cl. 132—41)

This invention relates to improvements in hair curlers and has particular reference to the type of curler in which a strand of hair is wound about and retained in curled position upon a mandrel.

An object of the invention is to provide an improved curler of simple, practical and durable construction, which is light in weight, and the mandrel of which is so formed as to facilitate drying of the curl wound thereon and the removal of said curl therefrom.

The above and other objects will appear more clearly from the following detailed description when taken in connection with the accompanying drawing which illustrates a preferred embodiment of the inventive idea.

In the drawing:

Figure 1 is a plan view of a curler constructed in accordance with the invention.

Figure 2 is a side elevation, with the curl confining member thereof in an inoperative position.

Figure 3 is an enlarged longitudinal section.

Figure 4 is a transverse section on the line 4—4 of Figure 3, and

Figure 5 is a sectional view illustrating the manner in which the wires of the mandrel are attached to the head of the curler.

Referring more particularly to the accompanying drawing, the numeral 6 indicates the head of the curler which is made of sheet metal and of circular formation in cross section, with one end thereof tapered or cut away as indicated at 7 and forming a grip by means of which the curler may be manipulated. Extending longitudinally from the head 6 is a mandrel upon which a strand of hair is adapted to be wound. In accordance with the present invention, said mandrel comprises a plurality of wires 8 which may be round or flat in cross section. These wires are attached to the head 6 so as to extend therefrom in longitudinally spaced relation and, for this purpose, the inner end of each wire is offset, as indicated at 9 in Figure 5, and said offset end is adapted, when the mandrel is being assembled, to be first inserted in to one of a series of annularly spaced openings 10 formed in the head 6. After being thus detachably connected to the head, the inturned outer ends 11 are brought into close proximity to each other and then secured together by a body of solder 12 which combines with said ends to form a recess or depression 13 in the outer end of the mandrel, the purpose of which will presently appear. When the elements of the mandrel are thus assembled, the same will be substantially

circular in cross section and slightly tapered throughout its length toward the outer end so as to aid in the removal of a curl therefrom, and with said elements spaced from each other it will be apparent that air will be permitted to more readily circulate through the hair wound upon the mandrel and thus facilitate drying of the curl.

Associated with the mandrel, is a clamping member 14 which is pivoted to the head 6 and is utilized to clamp the end of a strand of hair to the mandrel preparatory to winding said strand thereabout. Said member 14 is provided with two rows of apertures 15 to further aid in the drying of the curl wound upon the mandrel.

Also cooperating with the mandrel is a curl confining member 16 made from a single length of wire bent into loop form with its inturned ends 17 projecting through the head 6 at opposed points and constituting the pivot for the clamping member 14 as well as the member 16. The intermediate portions of the sides of said member 16 are outwardly bowed, as indicated at 18, to accommodate the curl wound on the mandrel, and the outer extremity or bight 19 of said member rotatably carries a stay 20 which is adapted to engage in the recess 13 in the outer end of the mandrel, whereby the member 16 is releasably held in its operative position. The stay 20 may be diamond-shaped in cross-section, as shown in the drawing, so that it will roll into place in the recess 13 between the ends of adjacent ones of the wires 8, with its inclined sides engaging said wires. This greatly facilitates the clamping of the curl confining member 16 in place.

A bowed leaf spring 21 is disposed in the head 6 with its extremities engaging the inner surfaces of said head and the adjacent end of the clamp 14 to exert pressure upon the latter to yieldably maintain the same in clamping relation to the mandrel.

What is claimed is:

1. In a hair curler, a mandrel in the form of an open-work cage of generally cylindrical form but tapering slightly towards one end, said mandrel comprising a tubular head, a plurality of wires extending from said head in spaced relation, and converging slightly towards each other, said wires having their ends turned inward and united so as to form a recess, a curl confining member of U-shape having its ends turned inwardly and journaled in said head, whereby said curl confining member is free to pivot on said head, a stay on the bight portion of said

curl confining member adapted to spring into said recess and thereby to hold said member in its operative position, an apertured clamping member having one end-portion pivotally mounted on said inturned ends of said curl confining member, and spring means acting between said head and said clamping member to urge said clamping member to seat itself on said mandrel.

2. A hair curler comprising a mandrel of skeleton construction, having a head, a plurality of wires disposed longitudinally in spaced relation and joined together at one end so as to form a recess, and said wires having a portion of their other ends offset laterally, apertures in said head, each adapted to receive one of said offset portions therein, a curl confining member having a pair of inturned end portions journaled in said head and said member carrying means adapted to engage said recess so as to hold it in operative position, and a clamping member journaled on said end portions of said curl confining member.

3. A hair curler comprising a mandrel of skeleton construction having a head, a plurality of wires disposed longitudinally in spaced relation and joined together at one end so as to form a recess, and said wires each having a portion of its other end offset laterally inwardly, apertures in said head each receiving one of said offset portions therein, a curl confining member substantially of U-shape having its ends turned inwardly and journaled in said head so as to pivot thereon, a stay rotatably mounted on the bight portion of said member, said stay being diamond-shaped in cross-section and adapted to roll into place in the said recess between the adjacent ends of said wires, whereby said member is held in curl confining position, an apertured clamping member having one end portion pivotally mounted on said inturned ends of said curl confining member, and spring means acting between said head and said clamping member to urge said clamping member to seat itself on the mandrel.

JOSEPH JACOBS.
